[57] CLAIM

The ornamental design for an ornament design, as shown.

DESCRIPTION

FIG. 1 is a perspective view of my new ornament;

FIG. 2 is a rear elevation;

FIG. 3 is a bottom plan view;

FIG. 4 is a front elevation;

FIG. 5 is a side elevation; and,

FIG. 6 is a second side elevation.

Phantom views illustrate the attachment of photographs to surfaces which are otherwise plane surfaces.

FIG. 1FIG. 2FIG. 3FIG. 4FIG. 5FIG. 6
